UNITED STATES PATENT OFFICE.

CARLOS G. BATES, OF DENVER, COLORADO.

EVAPORIMETER OR ATMOMETER.

1,332,659.

Specification of Letters Patent.

Patented Mar. 2, 1920.

Application filed June 3, 1919. Serial No. 301,590.

(FILED UNDER THE ACT OF MARCH 3, 1883, 22 STAT. L., 625.)

To all whom it may concern:

Be it known that I, CARLOS G. BATES, a citizen of the United States, and an employee of the U. S. Department of Agriculture, and residing in the city and county of Denver, State of Colorado, have invented a new and useful Improvement in Evaporimeters or Atmometers, of which the following is a specification.

10 The object of this invention is to provide a means whereby evaporation is produced at a rate which will coördinate approximately with the rate of evaporation from plants under all possible variations of light, heat, 15 wind and atmospheric conditions.

This object is accomplished by the enclosure of a moist linen wick between two layers of metal, the lower of which contains small openings, which permit the vapor 20 formed in and on the surface of the wick to escape by its own pressure to the outer atmosphere, as it does from the leaf of a plant. All other evaporimeters, or atmometers, so far as known, expose the entire 25 moistened surface to the atmosphere. Because of this difference, my invention is influenced by each of the various factors which contribute to evaporation more nearly like the plant than are other known evaporimeters.

For a full understanding of the invention, reference is made to the following description and drawings, in which—

Figure 1 is a cross section of the improved evaporimeter.

Fig. 2 is a top view of the under metal disk F of Fig. 1, showing the perforations, disassociated from the other parts.

Fig. 3 is a perspective view of the cover, 40 or upper metal layer, HN of Fig. 1, disassociated from the other parts.

Fig. 4 is a perspective of the instrument with the outer shell K and upper metal layer, or cover, HN removed.

Fig. 5 is a perspective view of the outer shell K removed from the other parts.

Corresponding and like parts are referred to in the following description, and indicated in all the accompanying drawings, by the 50 same reference characters.

The measurements hereinafter referred to are not essential to the invention, but are

preferred for the purpose of standardizing the instrument.

Referring to the drawings, the outer shell 55 K is made of 24 gage brass, 5 inches in diameter and 3 inches deep, riveted and soldered at side seam. The bottom of the shell is spun with a $\frac{1}{4}$ inch flange L, to which the wall or side is soldered.

60 A represents the inner tank, 4 inches in diameter at the top, 3 inches in diameter at the bottom, and $2\frac{3}{4}$ inches deep, spun of copper so as to result in a gage of about 24, with a flange M at the top edge.

65 The top of the tank is made of two thicknesses, B and B', of 24 gage brass, each 5 inches in diameter; the lower thickness spun with a $\frac{1}{4}$ inch flange, and the upper thickness B' spun with a crown of $\frac{1}{4}$ inch 70 and with a $\frac{1}{2}$ inch flange C. The lower thickness fits snugly inside the flange C of B', and the two flanges are soldered together with their edges flush, and the top thus assembled fits snugly over the wall or 75 side of the outer shell K. To this top the inner tank A is soldered concentrically, the flange M being attached to the layer B so that the tank A is suspended inside the shell K.

80 An opening K', $\frac{1}{2}$ inch in diameter, is made in the center of the top for the insertion of the brass tubing E, which is inserted so as to penetrate both thicknesses of the top and is securely soldered to both. For the purpose of filling the tank A with water, another perforation L', $\frac{1}{2}$ inch in diameter, is made through both thicknesses of the top at a point near the outer edge. In this 85 perforation is inserted and soldered to both 90 thicknesses of the top a brass tubing D, which extends slightly above the top B' and which is threaded to receive the cap D'.

The tube E is made of moderately heavy brass tubing, $\frac{1}{2}$ inch outside diameter, 95 $4\frac{1}{2}$ inches long, and projects 4 inches above the top B'.

The disk F is made of 16 gage brass, 4.44 inches in diameter, and is securely soldered to the top of the tubing E which will come 100 flush with its upper surface. The collar I is first threaded on to the upper end of the tubing E, for the purpose of reinforcing or supporting the disk F. The disk F is per-

forated with 64 drill holes F', each $\frac{1}{8}$ inch in diameter, which must be cut clean so as to leave no roughness on the disk. These perforations should be distributed as evenly as possible throughout the disk.

Two lugs G, from $\frac{1}{4}$ inch to $\frac{3}{8}$ inch in each dimension, are soldered to the underside of the disk F, at points on the outer edge that are directly opposite each other. Each 10 of the lugs G is drilled and threaded, so as to receive a $\frac{1}{8}$ inch machine screw J.

The upper metal layer, or cover, H is made of 20 gage brass, slightly more than 4.44 inches in diameter, spun with a $\frac{3}{8}$ inch flange N, turned at right angles to the main surface and gaged so as to fit closely over the edges of the disk F. Two slots O are cut in the lower edge of the flange N, at the points where such flange comes in contact with the two lugs G, when the upper 20 layer or cover H is fitted over the disk F. These two slots O should be just deep enough to admit the screws J. The two metal layers H and F are held securely together by $\frac{1}{8}$ inch round headed machine screws J, which when in place, will engage the edges of the two slots O in the flange N and the two lugs G. The two metal layers H and F must be flat, in order that the linen wick when placed between them will be closely in contact with each.

All exterior surfaces of the apparatus, including both surfaces of the disk F, but not including any part of the tank A, are neatly 35 and durably nickel.

In the operation of the improved mechanism, a stem wick P is placed inside of the tube E, extending from the bottom of the inner tank A to the upper surface of the 40 disk F. A thin circular disk linen wick O' is placed between the disk F and the cover H, so as to come in contact with the upper portion of the stem wick P. The upper end of the stem wick P, where it comes in contact with the linen wick O', is raveled and flattened out in the form of a rosette. The stem wick P, being in contact with the water placed in the inner tank A, feeds the circular wick O' with moisture. The placing 45 of the circular wick O' between the two metal layers H and F prevents the moist surface of the disk wick O' being exposed directly to the outside air, and operates so that the vapor formed in and on the surface 50 of the wick O' is not immediately carried away by the air, but must be forced out by its own pressure, as it is from the leaf of the plant.

The seamless tank A is not injured by the 60 freezing and thawing of the water in it, neither is the linen wick affected by freezing, and this permits the operation of the instrument at all seasons without recourse to non-freezing solutions.

65 The outer shell or tank K, and the nickel

plated surfaces throughout, are designed to protect the reservoir and lower portions from radiant energy, consequently to restrict evaporation to the region of the disk wick O'. To accentuate evaporation at that 70 point the metal cover H is usually coated on the upper surface with lamp-black for the absorption of radial energy, and while this is not an essential feature of construction, it is essential to the most successful 75 operation.

After the parts are assembled and the tank A filled with water the whole instrument is weighed. After a certain period of time the instrument and contents are again weighed 80 and the difference in the two weights determines the amount of evaporation produced.

I claim:

1. An improvement in evaporimeters, including a layer of linen inclosed between two 85 metal plates, one of which plates contains perforations, and both of which are attached, by means of a metal tube, to a closed seamless metal tank or reservoir, a linen wick extending through said tube and into 90 the seamless metal tank, which contains water, and connecting with the layer of linen between the two metal plates.

2. An improvement in evaporimeters, including a layer of linen inclosed between two 95 metal plates, one of which plates contains perforations, the other of which, in combination with lamp-black, is adapted to the complete absorption of radiant energy, and the transmitting of heat to the layer of 100 linen, and is so constructed as to exclude the moisture of precipitation from the layer of linen, both of which plates are attached, by means of a metal tube, to a closed seamless metal tank containing water, a linen 105 wick extending through such tube and into the seamless tank and connecting with the layer of linen between the two metal plates.

3. An improvement in evaporimeters, including a layer of linen between two metal 110 plates, one of which contains perforations, the other of which is constructed with a flange so as to cover entirely the perforated plate and the layer of linen, and, in combination with lamp-black is adapted to the 115 complete absorption of radiant energy and the transmission of heat to the layer of linen, both of such plates being attached, by means of a metal tube, to a closed seamless metal tank, the layer of linen between 120 the two metal plates being in contact with a rolled linen wick inclosed in the metal tube and extending into the seamless metal tank, so that it will come in contact with water placed in the metal tank and will transmit 125 moisture to the linen layer between two metal plates.

4. An improvement in evaporimeters, consisting of a polished metal shell with a cover or top consisting of two layers of 130

metal, so joined together that the layers will be slightly separated, a seamless metal tank suspended within the shell from the top or cover of the shell, a metal tube or stem extending through the top or cover of the shell and above it, surmounted by a perforated metal disk, and containing a rolled linen wick connecting with water in the seamless tank and with a layer of linen on the upper

surface of the perforated disk, a metal plate 10 with a flange covering the layer of linen and the perforated disk, and held in place by machine screws engaging notches in the flange of said metal plate, and threaded lugs attached to the lower surface of the perforated disk at its edge. 15

CARLOS G. BATES.
